UNITED STATES PATENT OFFICE.

JOHN C. RHODES, OF MATTAPoisETT, MASSACHUSETTS.

DESIGN FOR A TAG-FASTENER.

SPECIFICATION forming part of Design No. 13,128, dated August 1, 1882.

Application filed June 15, 1882. Term of patent 14 years.

To all whom it may concern:

Be it known that I, JOHN C. RHODES, of Mattapoisett, in the county of Plymouth and State of Massachusetts, have invented and produced a new and original Design for Tag-Fasteners, of which the following is a specification, reference being had to the accompanying drawings, forming part thereof.

Figure 1 represents a blank spangle or fastener as cut from thin sheet metal. Fig. 2 represents the same bent into rectangular shape, ready for use, by being inserted into suitable perforations formed in the tag.

A represents the central body portion or spangle forming the head of the fastener, which is formed circular, as shown, and provided at opposite sides with the tapering points or prongs B, each of which is provided on its opposite edge, and at a short distance from

the circular head A, with curved projections E, 20 as shown, and which curved projections E form a distinguishing and essential feature of my design, the said tag-fastener being formed from very thin sheet metal, and all parts having the essential outline or contour shown in 25 the accompanying drawings.

Having thus described my invention, what I claim is—

The design for a tag-fastener herein shown and described, the same consisting of the circular head A, having the tapering points B, 30 each of which is provided with the curved projection E, substantially as represented.

JOHN C. RHODES.
